CLAIM

The ornamental design for a battery housing, as shown and described.

DESCRIPTION

FIG. 1 is a top, left, front perspective view of a battery housing showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken line showing in FIGS. 1-7 is for the purpose of illustrating portions of the battery housing and forms no part of the claimed design.

1 Claim, 7 Drawing Sheets(56)
